UNITED STATES PATENT OFFICE.

WILLIAM U. GRIFFITHS, OF PHILADELPHIA, PENNSYLVANIA.

VALVE-OPERATING MECHANISM.

1,356,278.

Specification of Letters Patent. Patented Oct. 19, 1920.

Application filed October 21, 1918. Serial No. 259,096.

To all whom it may concern:

Be it known that I, WILLIAM U. GRIFFITHS, a citizen of the United States, and a resident of Philadelphia, in the county of Philadelphia and State of Pennsylvania, have invented an Improvement in Valve-Operating Mechanism, of which the following is a specification.

My invention relates to a valve operating mechanism and is particularly well adapted for the operation and control of valves employed in flush tanks of water closet apparatus for controlling the flow of water therefrom. It will be understood, however, that the principle of my invention may be applicable to other forms of construction and apparatus than that referred to.

The construction disclosed in this application relates to apparatus similar to that shown in my application, Serial No. 127,548, filed October 25, 1916, but is an improvement thereover in that the construction is simplified and is more compact.

One of the objects of my present invention is to provide a simple and efficient construction of valve structure and means for operating and closing the same.

Other objects and advantages of my invention will be pointed out in the detailed description thereof which follows or will be apparent from such description.

In order that the practical and commercial advantages of my invention may be more readily apparent, reference may be had to the accompanying drawings in which I have illustrated a form of construction which is at present preferred by me, but it will be understood that my invention is susceptible of embodiment in other forms than that shown without departing from the same as it is pointed out and defined in the claims.

In the drawings:

Figure 1 is a vertical, sectional view of a portion of a flush tank provided with my invention and showing the latter in side elevation; and Fig. 2 is a similar view with the operating mechanism in the position shown in Fig. 1, in dotted lines but with the valve in open position.

Referring to the drawings: 1 designates the bottom of a hopper for a water closet apparatus and 2 the upper end portion of

a flush pipe which projects through the said bottom into the said tank, the upper end of which constitutes a port leading from the said tank. 3 designates an overflow pipe of the character usually found in flush tanks of this character. 4 designates a valve for closing the upper end of the pipe 2, constituting the port leading from the flush tank as above stated, which valve is pivotally connected at 5 to an arm 6 which is pivoted upon a pivot 7 carried by a projection 8 which extends from the upper end of the pipe 2. The outer swinging end of the arm 6 is provided with a float 10. As a part of the means for effecting the opening of the valve and also for causing a tight closure thereof, I have provided a swinging arm 15 which is situated above the arm 6 and also is pivoted upon the pivot 7. The said arm, near its pivot end, is provided with a laterally extending projection 16, constituting a weight, which extends in a direction away from the swinging end thereof. It extends across a vertical plane through the pivot 7. The outer swinging end of the arm 15 is provided with an integral, plate-like portion 18, which extends transversely of and very nearly at right angles with respect thereto. The lower end portion of the said plate 18 is provided with a slot 19, which extends from the dotted line *a* to the dotted line *b*. The edge of the plate 18 is notched as shown so that the arm 6 may be inserted into the slot or opening 19 which extends between the dotted lines *a* and *b*.

When in closed position, as shown in Fig. 1, the weight of the arm 15 is greater than and over balances the weight of the projection 16, so that the upper end *a* of the slot 19 is in contact with the arm 6, as shown. The force, due to gravity, exerted by the arm 15, though diminished by the counter-balancing weight of the projection 16, tends to and does hold the valve 4 in tightly closed position upon the upper end of the tube or pipe 2. In order to open the valve 4, I have provided an operating rod 25 which is slidably mounted in a hollow post 26 which is secured to the bottom of the tank and extends upwardly therein to a point above the normal level of the water in the tank. The lower end of the said op-

erating rod 25 is provided with a weight 27 which is adjustably connected thereto. The adjustment of the weight 27 is desirable because it is intended that the operating rod 25 shall be operated automatically by the contact of a projection from the seat of a water closet or other movable member. It is apparent, therefore, that it may become necessary to adjust the member 27 in order 10 to vary its position so as to control the exact point at which the means for operating the same will contact therewith.

The upper end of the operating rod 25 is connected with the lower end of a link 30, 15 the upper end of which is connected with the one end of an arm 31 of a bell crank lever which is secured by means of a binding screw 32 to a pivot 33, which is pivotally supported upon a bracket 34 secured to the 20 upper end of the guiding and bearing post 26. The opposite arm 35 of the bell crank lever extends downwardly into the flush tank, and is provided at its lower swinging end with a pivoted tripping lever 36 which 25 lever is secured by means of a binding screw 37 to a pivot 38 which is pivotally supported in an opening through the end of the arm 35. The end of the pivoted tripping member 36 is extended as indicated at 40, such 30 extension being adapted to bear against the under side of the lower end portion of the arm 35 and to constitute a stop to limit pivotal movement of the tripping member 36 toward the left.

In operation, the operating rod 25 is first 35 moved upwardly through the tubular bearing post 26 by any suitable means, as, for instance, a projection from the rear portion of a water closet seat. Such upward movement causes an upward movement of the arm 31 of the bell crank lever and a simultaneous swinging movement of the arm 35 to the left. Such swinging movement carries the lower end of the tripping member 40 45 beyond the upper end of the plate 18 to the position shown in dotted lines in Fig. 1 of the drawings. In moving to such position, the lower end of the tripping member 36 contacts with the upper end of the 50 plate 18. The member 36, being pivoted, turns about its pivot and slides over the upper edge of the plate 18. After it passes over the upper edge of said plate, it returns to normal position with the projecting stop 55 extension 40 thereof in contact with the left edge of the lower end of the arm 35, as shown. When the means which holds the operating rod 25 in elevated position is released to permit the said rod to return to 60 normal position under the influence of its own weight and that of the weight 27, the bell crank lever is returned to normal position, the arm 35 being carried to the right. In moving to the right, the lower end of 65 the tripping member 36 contacts with the

surface at the left hand side of the upper end of the plate 18. The stop extension 40 being in contact with the underside of the arm 35, the tripping member 36 is prevented from turning about its pivot when 70 the arm 35 is being moved toward the right. Consequently the arm 15, by reason of the contact at such time of the tripping member 36 with the upper end portion of the plate, is swung to the right about its pivot, the 75 plate 18 being elevated. As the said plate is elevated, the lower end *b* of the slot 19 contacts with the arm 5 and lifts the same together with the valve 4 to open the latter. The arms 15 and 6 and the valve 4 carried 80 by the latter are swung to the open positions indicated in Fig. 2 of the drawings. As soon as the valve 4 is opened, the water begins to flow from the tank, through the pipe or tube 2. As the top level of the 85 water is lowered, the weight of the float 10 and of the lever 6 exerted upon the arm 15 by reason of the contact of the arm 6 with the lower end *b* of the opening 19, overcomes the weight of the projection 16 90 and the portion of the lever 15 to the right of the pivot 7, so as to cause pivotal movement of the arm 15 as well as of the arm 6 toward the left. The arms 15 and 6 for a time move in unison; that is, for a time 95 the arm 6 remains in contact with the lower end *b* of the slot or opening 19. However, after the arms 15 and 6 have moved into positions such that the valve 4 has arrived at a position near the port and is about to 100 close the same, the weight of the arm 15 overcomes the counterbalancing weight of the projection 16, so that the arm falls toward the left and in moving through the distance equal to that of the length of the 105 slot 19, acquires considerable momentum, so that when the upper end *a* of the said slot contacts with the arm 6, the latter is suddenly moved downwardly with considerable force, relatively speaking, so that the 110 valve 4 is caused to strike against the upper end of the pipe or tube 2 and tightly close the upper end thereof.

In the construction as illustrated the arms 6 and 15 move in the same vertical plane, 115 but it will be understood that the said arms may be so mounted as to swing or move in different parallel planes, in which case the slot 19 may be in off-set position with respect to the arm 15 and its plane of movement.

It will be observed that I have provided a construction which is quite simple. By actual experience it has been found that the same is very efficient in operation. The construction is compact and is of such a nature that it practically is never in need of repair.

Instead of providing means comprising parts 25, 30, 31, 35 and 36, for automatically operating the valve structure, I may operate 130

the latter by means of a lever and cord in known manner, the latter being connected at its lower end in the flush tank to the projection 41 upon the arm 6.

5 Although it is preferred that means operating upon the principle illustrated in the drawings for actuating and controlling the valve structure shall be employed, it will be understood that means of other construction 10 and operating upon a different principle may be employed. It will also be understood that the operation of the arm 15 is the same regardless of the manner in which the said arm 15 and the arm 6 are raised and 15 lowered.

I claim:

1. In combination, an arm pivoted at one end and having a valve secured intermediate its ends for closing an opening, a second 20 arm also pivoted at one end and adapted to swing in a plane coincident with or parallel to that in which the first named arm swings, a lever pivoted intermediate its ends and having a tripping member pivotally connected to an arm of said lever and adapted 25 to contact with said second named arm or a part carried thereby, and means whereby said tripping member is permitted to turn about its pivot in one direction from its normal position and held against turning movement in the opposite direction from such 30 position, whereby movement of said lever and member in one direction only causes movement of said second named arm, and 35 the said second named arm having means for contacting with the first named arm to cause movement thereof to effect opening and closing movements of said valve.

2. In combination, an arm pivoted at one 40 end, a valve secured to said arm at a point intermediate its ends, said valve being adapted to open and close a port leading from a flush tank, a float carried upon the outer swinging end of said arm, a second 45 arm pivoted at one end and swinging in a plane coincident with or parallel to that in which the first named arm swings, said second named arm being provided with a plate at its outer swinging end, said plate having 50 an elongated slot through which the first named arm extends, means for contacting with the said plate to cause swinging movement of the second named arm to carry the lower end of the said slot into contact with 55 the first named arm to lift the latter to open the said valve, and the upper end of said slot adapted to contact with the said arm to effect sudden closing movement of the first named lever and hold the latter with the 60 said valve in tightly closed position after the latter has once been closed.

3. In combination, an arm pivoted at one 65 end and carrying at its outer end a float, a valve secured to said arm intermediate its ends, said valve being adapted to close a

port, a second pivoted arm pivotally movable in a plane coincident with or parallel to the plane of movement of the first named arm, means for movably connecting the said arms, and means for effecting movement of the said arms to open and close the said valve. 70

4. In combination, an arm pivoted at one end and carrying at its outer swinging end a float, a valve secured to the said arm intermediate its ends and adapted to close a port leading from a flush tank, a second pivoted arm pivotally movable in a plane coincident with or parallel to the pivotal movements of the first named arm, the said second 80 named arm carrying at its outer swinging end means having movable connection with the said first named arm, the said arms being adapted to move together and independently of each other, and means for 85 causing movement of the said arms to open and close the said valve.

5. In combination, an arm pivoted at one end and carrying a float at its outer end, a valve secured to said arm intermediate its 90 ends and adapted to open and close a port leading from the flush tank of a water closet apparatus, a second arm pivoted at one end co-axially with the pivot of the first named arm, the said second named arm being provided with a part at its outer swinging end extending transversely of the length of the said second named arm, said part having an opening extending therethrough through which the first named arm extends, the upper and lower ends of said opening being adapted to contact with the said first named arm, and means for causing movement of the 95 said arms to open and close the said valve. 100

6. In a water closet apparatus, in combination, an arm pivoted at one end and carrying a float at its outer swinging end, a valve secured to said arm and adapted to open and close a port leading from the 110 flush tank of said apparatus, a second arm pivoted at one end and extending in the same direction from its pivot as the first named arm, said second named arm being provided at its outer swinging end with a 115 part extending transversely thereof, the lower end of said part having connection with the first named arm, a lever pivoted intermediate its ends, one of the arms of said lever extending toward the said arms 120 and having pivotally connected therewith a pivoted tripping member which is adapted to contact with the upper end of the part carried by the outer swinging end of the second named arm, and means for causing pivotal swinging movement of the said lever to swing the said tripping member across the upper end of the said part, the said tripping member sliding over the top of 125 said part when moving in one direction and 130

contacting with the upper portion of said part when being moved in the opposite direction to cause upward swinging movement thereof together with the said arms to effect opening movement of the said valve.

7. In a water closet apparatus, in combination, an arm pivoted at one end and carrying a float at its outer end, a valve secured to said arm intermediate its ends and 10 adapted to open and close a port leading from the flush tank of said apparatus, a second arm pivoted at one end and extending in the same direction from its pivot as the first named arm and being provided at its 15 outer end with a transversely extending part, said part being provided with an opening through which the first named arm extends and in which the said arm is relatively movable vertically, a lever pivoted intermediate its ends, one end portion of said lever extending toward the said arms and terminating in operative relation thereto, a tripping member secured to the lower end of

said portion, the said tripping member being permitted to move pivotally in one direction, means for preventing pivotal movement of the said tripping member in the opposite direction, and means for causing pivotal movement of said lever to cause movement of the end portion thereof carrying the said tripping member in a direction to slide the latter over the upper end of the part carried by the outer swinging end of the second named arm, the said tripping member pivoting as it slides over the upper 35 end of said part and the said tripping member contacting with the said part as it returns to normal position to cause upward swinging movement thereof together with the said arms to operate the said valve. 40

In testimony that I claim the foregoing as my invention I have hereunto set my hand this 20th day of September, A. D. 1918.

WILLIAM U. GRIFFITHS.
